(57) **CLAIM**

The ornamental design for a flexible shaft game club, as shown and described.

DESCRIPTION

FIG. 1 is a front view of a flexible shaft game club shown in use;

FIG. 2 is a reduced rear perspective view;

FIG. 3 is a rear perspective view with the shaft being shown in an alternate position;

FIG. 4 is a front perspective view of FIG. 2;

FIG. 5 is a top plan view of FIG. 2;

FIG. 6 is a bottom plan view of FIG. 2;

FIG. 7 is a front elevational view of FIG. 2;

FIG. 8 is a left side elevational view of FIG. 2;

FIG. 9 is a right side elevational view of FIG. 2;

FIG. 10 is a rear elevational view of FIG. 2; and,

FIG. 11 is a cross sectional view taken on line 11-11 of FIG. 10.

The broken lines representing a human in FIG. 1 and the areas within them depict environment only and form no part of the claimed design.
